UNITED STATES PATENT OFFICE.

CHARLES R. SHORT, OF DAYTON, OHIO, ASSIGNOR TO GENERAL MOTORS RESEARCH CORPORATION, OF DAYTON, OHIO, A CORPORATION OF DELAWARE.

ENGINE VALVE MECHANISM.

Application filed October 18, 1923. Serial No. 869,243.

To all whom it may concern:

Be it known that I, CHARLES R. SHORT, a subject of the King of Great Britain, residing at Dayton, county of Montgomery, 5 and State of Ohio, have invented certain new and useful Improvements in Engine Valve Mechanism, of which the following is a full, clear, and exact description.

This invention relates to an internal-combustion engine having a poppet valve operated by valve mechanism of the "one-head" type including a push rod extending from the engine crank case to a point adjacent the cylinder head, and a rocker arm 15 operated by the push rod for operating the valve.

It is among the objects of the present invention to compensate for variations in temperature whereby clearance between the 20 valve and its operating mechanism will remain substantially constant through the agency of apparatus which is more simple and reliable than employed heretofore.

Further objects and advantages of the 25 present invention will be apparent from the following description, reference being had to the accompanying drawings, wherein a preferred form of embodiment of the present invention is clearly shown.

30 In the drawings:

Fig. 1 is a fragmentary side elevation of an internal-combustion engine provided in the present invention.

Fig. 2 is a perspective view of a bracket 35 for supporting certain parts of the valve operating mechanism.

Fig. 3 is an end view of the engine shown in Fig. 1 looking in the direction of arrow 3 in Fig. 1.

40 Fig. 4 is a sectional view on an enlarged scale of the connection between the rocker arm bracket and the engine cylinder head.

In the drawings, an internal-combustion engine 20 includes a plurality of cylinders 21 attached to the crank case 22. The cylinders are provided with cooling fins 24 over which air is drawn into an air manifold 25 through the agency of an engine driven fan 26. Each cylinder is provided with two 50 valves, one of which is indicated at 30 in Fig. 3. The cylinders are connected together in pairs by means of a common superstructure 31 providing intake and exhaust ports and means for guiding all of the 55 valves of the cylinders. The valves are

maintained on their seats by means of springs 32 in the usual manner. The superstructure 31 supports a rocker arm bracket 33 comprising lever or foot members 34 joined by a member 36. Each lever 34 is 60 substantially V-shaped, comprising a yoke 34^a and branches 34^b and 34^c joined by a web 35. The branches 34^b support a rocker arm shaft 37 maintained in position by screws 38. The shaft 37 supports four 65 rocker arms 39, one arm for each of the four valves of a pair of cylinders. The rocker arms are maintained in position by means of springs 40, one spring being located between each pair of rocker arms. Each 70 spring 40 presses one of the rocker arms of each pair against an intermediate boss 41 extending from the yoke 36 and presses the other rocker arm of each pair against one of the lever members. 75

For each valve there is provided a push rod 50 having a foot portion 51 cooperating with a cam 52 on the engine cam shaft. By means of an adjustable ball and socket joint 53, 54, motion is transmitted from the push 80 rod 50 to the rocker arm 39. The ball 53 is attached to the lower end of a screw 55 threaded into the rocker arm 39 and maintained in adjusted position by nut 56.

Each arm 34^c of the levers 34 is attached 85 to the superstructure 31 by means of a link of material having a greater coefficient of expansion than the material of the lever, said links being provided by a pedestal 60 threaded into the superstructure 31 and provided with a shoulder 61 and a threaded extension 62. The extension 62 passes through 90 an aperture in the end of the lever arm 34^c and a nut 63 clamps the lever end against the shoulder 61. The yoke portion 34^a of 95 each lever 34 is fulcrumed upon a surface of the superstructure 31 by means of a button 65 having a central aperture and convex spherical surfaces on the opposite sides thereof which cooperate with the companion concave spherical recesses with which the superstructure 31 and the yoke 34^a of lever 34 are provided. A bolt 66 passes through a hole 67 in yoke 34^a through the washer or button 65, the holes in these parts being 100 larger in diameter than said bolt. In order to prevent the bolt from turning a lock washer 68 is provided with a series of fingers, one of which can be turned down as at 69 against a surface of one of the lever 110

members and another finger such as 70 may be bent up adjacent one of the flat surfaces of the head of the bolt.

It is apparent from the foregoing that a 5 rocker arm bracket is pivoted by means of its foot or lever members upon the cylinder superstructure and that each lever member is connected at one end to a post 60 constituting a tie member between the engine and 10 the lever member; and, at the other end, each lever member supports the rocker arm shaft.

As the temperature of the engine increases, the cylinder will expand at a greater 15 rate than the push rod 50 thereby tending to increase the clearance between the push rod and rocker arm or between the rocker arm and valve. In order to compensate for this increase in clearance, the link provided 20 by the post 60 will expand at a greater rate than the bracket 33 thereby causing the bracket to be tilted counterclockwise as viewed in Fig. 3 with increasing temperature. As the bracket is moved counterclockwise the rocker arm shaft 37 will be moved 25 downwardly to tend to compensate for the increase in clearance between the push rod and rocker arm. Conversely when the temperature in the engine decreases there will be 30 a tendency for the clearance to decrease but this tendency is balanced by upward movement of the rocker arm shaft 37 due to the fact that the post 60 contracts faster than the bracket 33.

35 While the form of embodiment of the present invention as herein disclosed, constitutes a preferred form, it is to be understood that other forms might be adopted, all coming within the scope of the claims 40 which follow.

What I claim is as follows:

1. Valve mechanism for engines comprising, in combination, a valve, a push rod operated by the engine, a rocker arm actuated by said rod for moving said valve, a lever 45 fulcrumed closely adjacent the engine cylinder and having an arm supporting the rocker arm and another arm terminating at a point spaced from the cylinder, and a link of material of greater coefficient of expansion 50 than the material of the lever connecting the engine with the end of the second mentioned lever arm.

2. Valve mechanism for engines comprising, in combination, a valve, a push rod operated by the engine, a rocker arm actuated by said rod for moving said valve, a lever 55 fulcrumed upon a surface of the engine and having an arm supporting the rocker arm and another arm terminating at a point 60 spaced from said engine surface, and a link of material of greater coefficient of expansion than the material of the lever connected with the engine at said surface and with the end of said second mentioned lever arm. 65

3. Valve mechanism for engines comprising, in combination, a valve, a push rod operated by the engine, a rocker arm actuated by said rod for moving said valve, a U-shaped lever having its yoke fulcrumed upon 70 the engine one branch of said lever supporting the rocker arm, and a link of material of greater coefficient of expansion than the material of the lever connected with the engine and with the end of the other branch 75 of said U-shaped lever.

In testimony whereof I hereto affix my signature.

CHARLES R. SHORT.
